UNITED STATES PATENT OFFICE.

AARON HORTON, OF DETROIT, MICHIGAN.

WASHBOARD.

1,338,930.

Specification of Letters Patent.

Patented May 4, 1920.

Application filed September 21, 1918. Serial No. 255,147.

To all whom it may concern:

Be it known that I, AARON HORTON, a citizen of the United States, residing at Detroit, in the county of Wayne and State of Michigan, have invented certain new and useful Improvements in Washboards, of which the following is a specification.

The present invention is a wash-board of that type having an opening in its rubbing front through which the face of a cake of soap is exposed, and the invention herein consists in the specific means for feeding said cake forward positively at intervals, rather than bearing it forward constantly by yielding force. A grating is usually provided to limit the forward movement of the soap, and it is found that when the cake becomes soft under the influence of heat and moisture, a follower which is constantly borne forward by spring pressure feeds the soap so rapidly that the grating embeds its front face and the cake is worn away and consumed more quickly than need be. The substitution of positive means actuated manually from time to time is therefore a little more than the replacing of one form of feed by another, because the labor of actuating this feed now thrown onto the operator finds its offset in the saving in the waste of soap.

The following specification describes the preferred manner of carrying out the invention.

In the accompanying drawings:

Figure 1 is a perspective view of the washing board embodying the present invention;

Fig. 2 is a vertical front to rear sectional view through the board;

Fig. 3 is a vertical transverse sectional view on the line 3-3 of Fig. 2, looking in the direction indicated by the arrows.

The board, except for the improvements embodying the present invention, is of the ordinary construction and includes the usual stiles or side pieces 1, top rail 2, and bottom rail 3. The board frame also includes an intermediate rail 4 and a backing board 5 which extends between the stiles 1 and vertically between the rails 3 and 4, as clearly shown in Fig. 2 of the drawings. The front of the board is as usual of sheet metal and is indicated in general by the

numeral 6, and this front extends from the top rail 2 to the bottom rail 3 and transversely between the stiles 1. From a point above the middle or intermediate rail 4 to the lower rail 3, the front 6 is corrugated as indicated by the numeral 7, to provide a rubbing surface, but above its corrugated portion it is preferably plain as shown in the drawings, and as indicated by the numeral 8. The portion 8 of the said front 6 is formed between the stiles 1 and at the upper end of the corrugated portion 7, with an opening 9 through which the forward side of the cake of soap is to project, as will be presently explained. The cake of soap is to be housed in a hood provided at the rear side of the board in the upper portion thereof and this hood is preferably of sheet metal and comprises sides 10, a top wall 11, and a bottom wall 12. The top wall 11 is preferably secured to the rear side or edge of the top rail 2, and also is preferably formed with an opening 13 normally closed by a door 14 hinged preferably at its lower side as at 15 at the lower side of the opening 13 and held closed at its upper side by means of any suitable latch device 16. The bottom or drain wall 12 is inclined downwardly and forwardly from the rear wall 11 and is united in any suitable manner to the rear side of the corrugated portion 7 of the front 6 and preferably extends over and rests upon the intermediate rail 4 so as to be afforded firm support. The numeral 17 indicates a shelf or horizontal partition wall which extends between the sides 10 above described and between the upper end of the corrugated portion 7 of the front 6 and the lower edge of the rear wall 11 of the said hood. This shelf is formed near its rear edge with one or more openings 18 so that any water flowing rearwardly over the surface of the shelf will be discharged on to the inclined bottom or drain wall 12 and will flow downwardly to the rear side of the corrugated portion 7 of the said front of the board, openings 19 being provided in the corrugated front 7 through which the soapy water may be returned to the rubbing surface of the board instead of being permitted to flow or drain back into the water in the tub. In order to limit the forward movement of the cake of soap through the open-

ing 9 and also to support the cake with its lower side in spaced relation to the upper surface of the shelf 17, the latter for a purpose to be presently explained, a suitable number of wires or small rods 20 are secured each at one end to or through the shelf 17 near the rear side thereof and are led from their said ends forwardly over the upper face of the shelf to the opening 9. 5 From this point the wires or rods are led vertically slightly in advance of the plane of the portion 8 of the front of the board and across the opening 9, and the upper end portions of the wires or rods are inserted 10 through openings 21 in the said portion 8 of the plain front at or adjacent the upper side of the opening 9 and are secured to the rear or inner side of the said portion 8 in any suitable manner. It will now be understood 15 that when a cake of soap, indicated by the reference letter C is introduced into the soap compartment through the opening 13, the door 14 having been swung open, the lower side or edge of the cake will rest upon 20 the horizontal portions of the wires which extend over the upper surface of the shelf 17 and which might be called rails designated specifically by the reference numeral 22, and the forward face of the cake will rest 25 against a grating composed of the vertically extending portions 23 of the said wires or rods and will project slightly beyond the forward face of the portion 8. 30 As before stated, means is provided for holding the cake against the grating and for feeding the cake positively forward as it is worn away, and this means comprises a follower having a head 24 preferably comprising a plate of sheet metal provided with a 35 marginal rearwardly projecting flange 25, the flange at the lower edge of the plate resting upon the rails 22 with the forward face of the plate presented to the rear face of the cake of soap C. By an attaching plate 26, 40 one end of a feed screw 27 is rigidly secured to the rear side of the head 24 and fitting this screw is an internally threaded sleeve or tubular nut 28 which is provided exteriorly with a circumscribing rib 29. This 45 rib rests against an inwardly extending flange 30 which surrounds an opening 31 in the rear end of a hollow thimble 32 fitted through and secured to the rear wall 11 of the soap compartment 10, the nut rearwardly of its rib 29 fitting rotatably 50 through the opening 31 as clearly shown in Fig. 2 of the drawings. In order that the nut 28 may be rotated so as to forwardly or rearwardly feed the screw 27 and impart 55 corresponding motion to the follower head 24, a hand wheel or the like 33 is keyed or otherwise secured upon the rear end of the nut and at its forward side the hub of this wheel engages against the rear side of the 60 flange 30 of the thimble 32. In this manner 65

the nut 28 is held against longitudinal movement in either direction in the thimble 32 and consequently when it is rotated through the medium of the hand wheel 33, the feed screw 27 will be advanced or retracted so as 70 to correspondingly move the follower.

From the foregoing description of the invention it will be understood that after the feed screw has been drawn rearwardly so as to retract the follower 24, the door 14 75 may be opened and a cake of soap inserted into the hood with its forward side seating in the opening 9 and its rear side presented to the follower 24, the lower side of the cake being supported above the shelf 17 by 80 the track portion 22 of the wires 20. The feed screw 27 may then be fed forwardly by rotating the hand wheel 33, so as to cause the follower head 24 to bear more or less firmly against the cake of soap and force the 85 same against the restraining or grate portion 23 of the said wires 20. This adjustment of the follower may, of course, be repeated as the cake of soap becomes worn down. It will also be understood that any 90 water rich in soap and squeezed from clothes in rubbing the clothes over the face of the cake of soap will not merely run down over the face of the board and into the more or less dirty water in the tub, but will flow 95 rearwardly over the shelf 17, the board being naturally inclined in a direction to cause such flow, and will pass through the opening or openings 18 and be directed by the bottom 12 through the openings 19 and 100 on to the rubbing surface by the time the clothes have been shifted to said surface. In this manner there is little or no waste of 105 relatively clean water rich in soap and the same may be utilized in cleansing the clothes.

In order to assist in guiding the follower 24 in its movement within the soap container, the shelf 17 is stamped up midway between its ends to form an upstanding rib 110 35 extending in a front to rear direction, and the bottom flange 25 of the follower is likewise stamped up between its ends so as to provide spaced depending ribs 36 forming between them a groove or channel 37 115 into which the rib seats. To further assist in guiding the follower, plates 38 are secured to the opposite side walls 10 of the soap receptacle and are provided with inwardly laterally projecting flanges 39 which 120 overlie the upper corners of the follower in the manner clearly shown in Fig. 3 of the drawings.

Having thus described the invention, what is claimed as new is:

In a wash-board, a rubbing surface having an opening crossed by a grating, a shelf extending rearward from the lower edge of said opening for supporting a cake of soap, a follower head, a screw projecting rigidly 130

therefrom to the rear, and means for guiding the head for movement over the shelf toward and from said grating; combined with a hood carried by the wash-board and inclosing said shelf and follower, a thimble secured through the rear wall of the hood and having an internal flange at its rear end,

a tubular nut threaded on said screw and having a rib rotatably mounted inside said flange, and a hand wheel fast on the nut 10 with its hub against the outside of said flange.

In testimony whereof I affix my signature.
AARON HORTON. [L. s.]
